UNITED STATES PATENT OFFICE.

HENRY C. HUGHES, OF GILLSBURG, MISSISSIPPI.

COTTON-CULTIVATOR.

SPECIFICATION forming part of Letters Patent No. 449,418, dated March 31, 1891.

Application filed October 25, 1890. Serial No. 369,286. (No model.)

To all whom it may concern:

Be it known that I, HENRY C. HUGHES, a citizen of the United States, residing at Gillsburg, in the county of Amite and State of Mississippi, have invented certain new and useful improvements in Cotton-Cultivators; and I do hereby declare the following to be a full, clear, and exact description of the invention, such as will enable others skilled in the art to which it appertains to make and use the same.

My invention consists in a new and improved cotton-cultivator which can be changed to operate with either a reciprocating or a revolving hoe or chopping-blades, this change being effected in a few moments by any person; and my invention comprises other new and novel features, as will be hereinafter fully described and claimed.

Referring to the accompanying drawings, Figure 1 is a top plan view of my new and improved cotton-cultivator, showing the reciprocating hoe arranged in its operative position. Fig. 2 is a perspective rear view of the same. Fig. 3 is a top plan view showing the cultivator arranged with the rotary hoes or choppers. Fig. 4 is a detail view of one of the scrapers.

The same numerals of reference indicate corresponding parts in all the figures.

Referring to the several parts by their designating-numerals, 1 indicates the tongue of my new and improved cotton-cultivator, and 2 indicates my iron axle, which is preferably two and one-half inches in diameter. The tongue is mounted on the axle by means of a boxing 3, passing around the axle and secured to the lower side of the tongue, collars 4 holding the tongue at the center of the axle. A brace 5 connects the tongue with the axle on the left-hand side of the tongue, the rear end of this brace-rod being curved around the axle in an eye. The main wheels 6 are rigidly secured on the ends of the revolving iron axle, and upon the right-hand end of the axle is adjustably secured a large bevel-wheel 7, either by means of a set-screw passing through its hub or by a key 8, fitting in a longitudinal groove 2^a, which is formed in the right-hand half of the axle. With this large bevel-wheel 50 meshes a bevel-pinion 9, the deep sides of which are formed with a series of radial open-

ings 10, which are threaded, for the purpose hereinafter specified. This pinion is pivotally mounted on the outer end of a supporting-arm 11, bolted at its inner end to the side 55 of the tongue.

Across the hollow back of the pinion is secured a bearing-plate 12, having pivot-openings 12^a formed in it at different distances from its center to regulate the length of 60 stroke of the pitman 13. This pitman is secured at its outer end by a pivot-bolt 14, secured in either one of the openings 12^a, and its inner end is mounted on a short crank-shaft 15. The inner end of this crank-shaft 65 is mounted in a longitudinal opening 1^a, formed in the rear end of the tongue, while its outer end is mounted in the rear end of a metal bracket 16, bolted to the rear end of the tongue. The projecting rear end of the 70 crank-shaft is squared, and its extremity is threaded for the reception of a nut 17.

18 indicates the reciprocating hoe, the stem of which is formed with a series of square openings 18^a to adapt it to fit on the squared 75 rear end of the crank-shaft, and by means of this series of openings the cutting-blade can be raised or lowered to the height desired.

On the rear end of the tongue, on each side thereof, are bolted the stems 19 19 of two 80 scrapers, the upper part of these stems being formed with a series of holes 19^a, so that they can be raised or lowered to adjust the height of the blades 20 on their lower ends. The scraping-blades are of the form shown, having their inner vertical edges 20^a bent at a considerable angle to the body of the blade, and are bolted to the flat lower ends of the stem 19, the said ends being formed with two series of bolt-holes 19^b, so that the blades can 90 be moved to increase or decrease the space between their inner edges. To the rear end of the tongue are secured by the bolts 21 the two U-shaped standards 22 22, having at their lower ends the blades 23, and the rear parts 95 of these frames 22 are connected by a bracket 24, through the ends of which pass adjusting-screws 25, the inner ends of which bear against the frames 22, so that by turning these screws the space between the blades 23 100 can be increased or lessened, as desired. It will be seen that when the machine is drawn

forward the bevel-wheel 7 will revolve the pinion 9 and the hoe 18 will, through the connecting-pitman 13, be reciprocated to each side at regular intervals. The blades 20 5 scrape each side of the row in advance of the reciprocating cutting-blade, while the blades 23 mold or shape the hill after each stroke of the hoe.

When a revolving cutter is desired, the bracket 16 is removed, and also the crank-shaft, the pitman 13, and the reciprocating hoe. The bevel-pinion 9 is then removed from the arm 11 (which is also taken off) and mounted on a pivot-bolt 26, which screws 10 firmly into the opening 1^a in the rear end of the tongue. The large bevel-wheel 7 is then 15 slid in on the axle until it meshes again with the bevel-pinion, and is there keyed firmly in position. 27 represent cutting-blades, the 20 stems or handles 28 of which are threaded at their ends and screw into the series of radial openings 10 in the bevel-pinion. One, two, or more of these blades may be thus set in position, and as the large bevel-wheel 7 revolves 25 with the axle it revolves the bevel-pinion with its cutting-blades, thus giving an effective and thoroughly practical rotary hoe or cutter. The U shape of the frames 22 gives room for the revolving blades, as will 30 be seen. The U-shaped frames 22 can be readily detached from the machine and still leave a complete cotton-cultivator.

A U-shaped frame 29 is secured upon the tongue at the point shown, and a transverse rod 30 passes through the upper end of this 35 frame and through handles 31, which are bolted at their forward ends to the tongue of the machine and extend back at their rear handle ends to the back of the machine within 40 convenient reach of the driver. It will now be seen that by taking hold of these handles and raising their rear ends the driver can swing the forward end of the tongue down, elevating its rear end so as to lift the 45 several blades out of the ground, which is

very necessary when a stump or other obstruction is met or in driving the machine from one field to another.

From the foregoing description, taken in connection with the accompanying drawings, 50 the construction, operation, and advantages of my invention will be readily understood.

It will be seen that my new and improved cotton-cultivator is strong and durable in its construction and exceedingly effective in its 55 operation, and that it can be changed in a few moments from a reciprocating to a rotary cutter.

Having thus described my invention, what I claim, and desire to secure by Letters Patent, is—

1. The combination of the revolving axle, the tongue mounted thereon and having the longitudinal opening 1^a in its rear end, the removable bracket 16, the large bevel-wheel 65 adjustably secured on the axle, the bevel-pinion 9, mounted on a removable supporting-arm formed with the series of radial threaded openings 10 and having the bearing-plate 12 secured to it, the removable 70 crank-shaft, the connecting-pitman having the pivot-bolt at its outer end, and the reciprocating hoe adapted to be mounted on the rear end of the crank-shaft, substantially as set forth.

2. In a cultivator, the combination of the U shaped frames 22, secured at their forward ends to the machine and having the blades 27 at their lower ends, the bracket 24, connecting the rear part of said frames, and the adjusting-screws 25, working in the ends of the bracket and bearing against the frames 22, substantially as set forth.

In testimony whereof I affix my signature in presence of two witnesses.

HENRY C. HUGHES.
